UNITED STATES PATENT OFFICE

JAMES A. MACDONELL, OF LIMA, OHIO

COMBINATION PERCUSSION AND ROTARY DRILL

Application filed May 9, 1931. Serial No. 536,175.

This invention relates to drilling tools and particularly to those of the character commonly used for the drilling of deep wells.

In the drilling of such wells it has been common to use what is known as "percussion drills" and also what is known as "rotary drills", each having certain advantages over the other in connection with certain classes of work, but these so far as I am aware, have always been used separately.

The object of my invention is to provide a drill head of the character described, which will include bits of both of said types adapted to operate conjointly and thereby combine the separate advantages thereof and enabling work to be more rapidly performed than is possible by the use of either type alone.

The invention is fully described in the following specification, and while in its broader aspect it is capable of embodiment in numerous forms, one embodiment thereof is illustrated in the accompanying drawing, in which—

Figure 1 is a side elevation of a drill head embodying the invention, with its lower end submerged in a well being drilled and with the bit members in normal relation. Fig. 2 is a central vertical section thereof on the line 2—2 in Fig. 1, with parts in full. Figs. 3 and 4 are cross-sections, respectively, on the lines 3—3 and 4—4 in Fig. 1. Fig. 5 is a view similar to Fig. 1, with the upper portion of the drill head broken away and having a modified form of rotary cutting member, and Fig. 6 is a section on the line 6—6 in Fig. 5, with a part in full.

Referring to the drawing, 1 designates the stem or shank of the drill head, which is adapted to be attached at its upper end to the lower end of a drill pipe for rotary and reciprocatory movements therewith.

A bit 2 of the type commonly used for percussion drilling and which, in the present instance, is shown as being of broad blade type, is removably attached to the lower end of the stem 1, and preferably has a channel 3 therethrough in communication with a channel 4 extending through the stem 1 and through which water may be introduced into

the bottom of the well during a drilling operation, as well understood in the art.

A collar 5 is mounted for reciprocatory movements on the stem 1 and is caused to have rotary movements therewith by reason of a feathered or other suitable connection of the two.

A coiled expansion spring 6 encircles the stem 1 between the collar 5 and a fixed collar 7 on the stem to exert a yielding downward pressure on the collar, and the downward stroke of the collar is limited by the feathers on the collar striking the lower end of the grooves 8, in which they work, or in any other suitable manner.

A rotary type of bit 9 is detachably threaded or otherwise suitably secured to the collar 5. This bit has its lower end forked to straddle the percussion bit 2 and to provide a cutting blade 10 at each side of the bit 2. The cutting end of the rotary bit 9 is normally disposed below the end of the percussion bit 2 to adapt the latter during a rotary cutting movement of the former to be axially reciprocated to have percussion drilling movement.

In the form of the invention shown in Figs. 5 and 6, the rotary bit comprises a forked member 12, which is mounted at its upper end for reciprocatory movements on the stem 1, and for rotary movements therewith, and has the lower ends of its fork arms provided with transversely projecting studs 13 carrying cutting disks 14, which during a rotation of the drill head cause a rotary cutting of the bottom surface of the well being drilled, as is apparent.

In the use of my improved tool, the drill head, for the purpose of using the percussion bit in the drilling operation, is reciprocated in the usual manner to cause such bit to have repeated striking engagement with the bottom of the well, and at the same time the drill head is rotated so as to cause the rotary bit member to have rotary drilling coaction with the well bottom, the same as is common in the use of tools of the rotary type. It is apparent that by this combined percussion and rotary drilling actions, a well is more quickly drilled than when either a percussion or rotary type of drill is used alone.

- I wish it understood that my invention is not limited to any specific construction, arrangement or form of the parts, as it is capable of numerous modifications and changes without departing from the spirit of the claims. I also wish it understood that in carrying out my invention, rotary and percussion bits of the type commonly employed, may be used.
- Having thus described my invention, what I claim as new and desire to secure by United States Letters Patent is:
1. In a drill head of the character described, a stem, a percussion bit carried by the stem and a rotary bit carried for rotary movements with the stem, and for reciprocatory movements relative thereto and normally standing projected relative to the percussion bit.
  2. A drill head of the class described, including a stem, a percussion bit attached to the lower end of the stem, a rotary bit of forked form straddling the percussion bit and mounted on the stem for rotary movements therewith, and axial reciprocatory movements relative thereto, and means yieldingly acting on the rotary bit to normally maintain its cutting end projected beyond that of the percussion bit.
  3. The combination with a drill stem, of a percussion type bit rigidly secured thereto, a rotary type bit splined to said stem, and resilient means for maintaining said rotary type bit projected while said stem is reciprocated.
- In testimony whereof I have hereunto signed my name to this specification.

JAMES A. MACDONELL.
